[57] CLAIM

An ornamental design for a transparent communion table, as shown and described.

DESCRIPTION

FIG. 1 is a front perspective view of a transparent communion table showing my new design;

FIG. 2 is a front elevational view thereof, the rear elevational view is a mirror image;

FIG. 3 is a top plan view, the bottom plan view is essentially the same; and,

FIG. 4 is an end elevational view thereof, the opposite end is a mirror image.

The broken line showing of the message “Do this in Remembrance” is for illustrative purposes only and forms no part of the claimed design.
